CLAIM

The ornamental design for a container for fragrant liquids, as shown and described.

DESCRIPTION

FIG. 1 is a front elevational view thereof, it being understood that the front elevational view is identical to the rear and both side elevational views;

FIG. 2 is a bottom plan view thereof;

FIG. 3 is a top plan view thereof;

FIG. 4 is a perspective view of the front and a portion of the sides, according to our new design, it being understood that the perspective view of the rear and a portion of the sides would be identical;

FIG. 5 is an exploded perspective view of the front and a portion of the sides thereof, it being understood that the exploded perspective view of the rear and a portion of the sides would be identical; and,

FIG. 6 is an exploded perspective view of the front and a portion of the sides thereof, it being understood that the exploded perspective view of the rear and a portion of the sides would be identical.
